MAILING PIECE

Harold M. Petzold, Portland, Oreg.

Application July 5, 1939, Serial No. 282,892

6 Claims. (Cl. 229—92.1)

The present invention relates to improvements in mailing pieces and the primary object of the invention is to provide a mailing piece including a return envelope having an area for containing an advertisement or other communication, and a combined record card, order blank and currency receptacle.

Another object of the invention resides in the provision of a mailing piece of the character described wherein the card and envelope may be readily assembled for mailing without likelihood of confusion or mistake by the user.

A further object of the invention is to provide a mailing piece including an improved currency receptacle.

A still further object lies in the provision of a mailing piece including a currency receptacle and an envelope guarding against surreptitious access to the receptacle.

Yet another object is to provide a mailing piece including an envelope portion so constructed as to facilitate authorized opening thereof.

The invention also aims to provide a mailing piece including a record card and an envelope so constructed that the envelope may be readily torn or severed from the record card so that the latter may be compactly filed.

The invention further aims to provide a mailing piece including a coin receptacle having an access opening and an envelope foldably secured thereto in a manner whereby the access opening of the coin receptacle is covered by a double layer of the envelope material.

A further feature of the invention is the provision of a mailing piece including a combined currency receptacle and order blank so constructed and arranged as to encourage the insertion of currency in the receptacle prior to the recording of the order in the appropriately designated order blank area, thereby tending to prevent inadvertent sealing of the envelope without the proper enclosure of currency.

Other objects and advantages of the invention will become apparent during the course of the following detailed description, taken in connection with the accompanying drawing, forming a part of this specification and in which drawing—

Figure 1 is a plan view of the inside of my improved mailing piece with the component parts in unfolded relationship.

Figure 2 is a view similar to Figure 1 but showing the record card partially folded into the envelope.

Figures 3 and 4 are sectional views substantial-

ly along the lines 3—3 and 4—4 respectively, of Figure 1.

Figure 5 is a view similar to Figure 2 but showing the record card folded between the front and back of the envelope.

Figures 6 and 7 are views of the back and front sides of the completely folded mailing piece.

In the drawing, which for the purpose of illustration shows only a preferred embodiment of the invention, and wherein similar reference characters denote corresponding parts throughout the several views, 10 designates the mailing piece including a card 11 and wrapper or envelope 12.

Formed of two plies 15 having their inner marginal edge portions united as by adhesive 16, the card provides a pocket 17 for currency or check accessible thru a slit 18 inwardly of a given marginal end 19. One side of the card is appropriately designated at 20 for the entry of an order by an intending purchaser, a portion of the opposite side being appropriately designated at 21 for the entry of the purchaser's mailing address. Adjacent the designated portion 21 is a blank portion 22 for the reception of adhesive 23 for attachment of the wrapper or envelope 12.

Including a front panel 25 appropriately designated on its exterior side, as at 26, with the seller's mailing address, and a back panel 27 foldably joined to the lower edge 28 of the front panel, the wrapper is adapted to be secured to portion 22 of the card along the marginal portion 29 of the back panel, for folding along a line 30 intermediate the portions 21—22 of the card.

As will be noted from an inspection of Figures 1 and 2, the interior of the front panel 25, and the interior of a portion 31 of the back panel, contain indicia 32, such as an announcement or advertisement soliciting an order. It will also be noted that the front panel 25 and card 11 may be folded into coincident relation, as shown in Figure 5, only after the card 11 and back panel 27 are folded together. When so folded, certain marginal edges 33 of the back panel are slightly inwardly spaced from corresponding marginal edges 34 of the card.

Secured to the front panel for folding inwardly along edges 35—37, are right, left, and top flaps 38—40, adapted to be turned over said marginal edges 33—34, without creating a buckling or bulging upon sealing, because of the spaced relation of the edges 33—34. The right flap 38 is relatively narrow and provided with adhesive 41 throughout its width, and includes an upper end portion 42 devoid of adhesive. The relatively

wide left flap 39 is provided along its outer marginal portion 43 with adhesive 44, the inner marginal portion 45 and upper end portion 46 being devoid of adhesive. Along its outer marginal portion 47, the top flap 40 is provided with adhesive 48 terminating short of the end portions 49 thereof.

In the utilization of my improved mailing piece, a prospective purchaser will unfold the same and read the advertising matter 32 interiorly of the wrapper, as shown in Figure 1. The purchaser's mailing address may then be entered in the space 21 and currency or check inserted into pocket 17 thru the access slit 18. Upon reversing the card, the purchaser's order may be entered into the space 20, as shown in Figure 2. The card 11 is then folded into coincidence with the front panel 25, as shown in Figure 5, after which the right and left flaps 38-39 are folded over and adhered to the back panel 27, the relatively wide left flap 39 overlapping the back panel and forming an additional layer covering the access slit 18 leading to the currency pocket and thereby tending to prevent a coin which may have worked its way into the slit from cutting or wearing thru the envelope. Finally the top flap 40 is folded over and adhered to the back panel and also to the ungummed upper end portions 42, 46 of the side flaps.

Upon receipt of the mailing piece, the seller may insert a letter-opener beneath the ungummed portions 49 of the top flap to sever the same, whereupon the letter-opener may be inserted beneath the ungummed portions 42, 46 of the right and left flaps for severing the letter. The card 11 containing the record of the order may be thereupon readily detached from the wrapper and when so detached, constitutes a filing card or seller's record of the transaction.

The relatively wide left flap 39 allows for an increase in the thickness of the left side of the currency holding card 11 when a thickness of coin or bills is inserted thru the access slit 18. Additionally, the flap at its gummed portion 43, upon folding, will extend beyond the access slit 18 so as to obtain a firm pasting support even tho the thickness of currency in the pocket 17 produces a bulge at the slit 18.

Various changes in the shape, size and arrangement of parts may be made in the form of invention herein shown and described without departing from the spirit of the invention or the scope of the following claims.

I claim:

1. A mailing piece comprising a card providing an area on one side appropriately designated for the entry of an order by a purchaser and an area on the opposite side appropriately designated for the entry of the purchaser's mailing address, a wrapper including a front panel provided on its exterior side with a seller's mailing address and on its interior side with an advertisement soliciting an order, flaps foldable over the interior side of the front panel, said card being foldably joined to the interior side of a given one of said flaps, the edges of said card extending beyond opposite sides of the fold, the remainder of said flaps being arranged to secure the card within said wrapper for transmission thru the mails, said card being readily detachable from said wrapper upon receipt of the mailing piece by the seller and when so detached constituting a file card or seller's record of the order.

2. A mailing piece comprising a card, and an envelope therefor, said envelope including a front, a back comprising a pair of foldably joined sections, one of said sections being foldably joined to the front and the other of said sections being secured to a margin of said card with the edges of said card extending beyond opposite sides of the folding junction of said sections, whereby said card is foldable into substantial coincidence with the inside of said back as a pre-requisite to folding the back into substantial coincidence with the front, and means to secure said front and back in said folded relation.

3. A mailing piece comprising a card and an envelope therefor including a back foldably joined to the card, the edges of said card extending beyond opposite sides of the fold, a front foldably joined along a given edge to the back, side flaps foldably joined to the front along edges thereof adjacent said given edge, adhesive means for securing limited portions of said side flaps to said back, a top flap foldably joined to the front along an edge opposite said given edge, and adhesive means for securing a limited portion of said top flap to said back and to sections of said side flaps beyond said limited portions, whereby to permit the insertion of a letter-opener beneath the top flap, the severance of said top flap being a pre-requisite to the insertion of a letter-opener beneath the sections of said side flaps beyond said limited portions.

4. A mailing piece comprising a card and an envelope therefor including a back foldably joined to the card, the edges of said card extending beyond opposite sides of the fold, a front foldably joined to the back whereby said card is disposed therebetween, and means to secure the front and back in folded relation with said card disposed therebetween.

5. A mailing piece comprising a card including two plies of sheet material adhesively secured together along their margins to form a pocket therebetween, one of said plies being slit inwardly of a given margin thereof for access to said pocket, and an envelope for said card including a back foldably joined to the card, the edges of said card extending beyond opposite sides of the fold, a front foldably joined to the back, and gummed flaps foldably joined to the front and adapted to overlap portions of said back whereby to secure said front and back in folded relation with said card therebetween.

6. A mailing piece comprising a card, and an envelope therefor including a back foldable into substantial coincidence with the card, the edges of said card extending beyond opposite sides of the fold, a front foldable into substantial coincidence with the back whereby said card is disposed therebetween, side flaps joined to the front and foldable over portions of the back, one of said flaps being relatively wide and the other relatively narrow, adhesive material extending along the outer margin of said wide flap and thruout the width of said narrow flap, and terminating short of given ends of said flaps, a top flap joined to the front and foldable over said given ends, and adhesive material extending along the outer margin of said top flap for securing said top flap to said given ends and to the back.

HAROLD M. PETZOLD.
